O. J. HOLMES.
FIRE EXTINGUISHER FOR PROJECTING FOAM AND LIQUID.
APPLICATION FILED AUG. 19, 1916.

1,361,997.

Patented Dec. 14, 1920.

ATTY.

UNITED STATES PATENT OFFICE.

OSCAR J. HOLMES, OF ST. LOUIS, MISSOURI.

FIRE-EXTINGUISHER FOR PROJECTING FOAM AND LIQUID.

1,361,997.

Specification of Letters Patent. Patented Dec. 14, 1920.

Application filed August 19, 1916. Serial No. 115,867.

To all whom it may concern:

Be it known that I, OSCAR J. HOLMES, a citizen of the United States, and resident of St. Louis, in the State of Missouri, have invented certain new and useful Improvements in Fire-Extinguishers for Projecting Foam and Liquid, of which the following is a full, clear, and exact description, reference being had to the accompanying drawings, forming a part hereof.

My invention relates to an improved fire extinguisher for projecting both a fire-smothering foam and a fire-extinguishing liquid, either separately or simultaneously; and my invention consists in the novel construction and combination of parts herein-after described, and particularly pointed out in the claims hereunto appended.

The object of my invention is to provide improved means which shall be located in a single fire-apparatus tank (without partitions or division therein), for either projecting foam generated in said tank, or the solid stream of liquid, and for projecting from said tank a limited proportion of foam and liquid which the operator may desire to be projected, whereby a single fire-apparatus may be used for extinguishing oil-fires (or any incipient fire) at close range, with foam; at a greater distance with a combination of foam and liquid, and at a still greater distance with liquid alone.

In the drawings,

Figure 1 is a vertical section of a fire-extinguisher tank, having my invention applied thereto.

Fig. 2 is a detail plan-view of a rotary-valve, used (in the present illustration of my invention) for controlling the flow of foam from the tank.

Fig. 3 is a detail section of said rotary-valve, taken on the line 3-3 of Fig. 2.

Fig. 4 is a detail plan-view of the rotating combined acid-bottle holder foam-valve stem, and the T pipe-connection at the upper end of the siphon-pipe, and the foam-valve as applied thereto in the present instance, and

Fig. 5 is a detail view, partly in section, of the combined bottle-holder, the bottle, and suitable operating connections.

In the present form of my invention, the numeral 1 designates a rotatable mixing-valve, for controlling the flow of foam from the tank, and which valve has on its back a seat 2 that is U-shaped in cross-section

and fixed in place by means of solder or rivets upon the copper valve 1.

Said valve, in the present case, is a circular disk of sheet copper, having a discharge-opening 18, and a central perforation 17^a for receiving a pivot-screw 17, by means of which screw the said disk is pivotally mounted upon the adjacent face of an exit-T 3 of the discharge-pipe.

Said discharge-pipe consists of a siphon-pipe 11, extending down to a point near the bottom of the tank 9; a strainer 10 at the lower end of said pipe 11; the said T 3; a return-bend 20', which passes through an aperture formed in the breast 22 of the said tank, and is connected with the upper end of said T 3 by means of a short extension, all of the said elements being located, as shown, upon the interior of said tank.

A suitable flexible hose 12 has one end connected to the outer end of said return-bend 2, and its opposite end fitted with a common nozzle 13 and a shut-off cock having the usual handle 13^a, whereby the discharge of foam and solid stream of liquid from said tank can be controlled by the operator.

A common cap 8 is fitted to the top of the said tank, in the usual manner, for the purpose of affording access to the interior of the tank, in charging the same, as well as for purposes of cleaning out the waste material, it being understood (of course) that said cap should be fitted in place in such a manner as to form a tight joint, to prevent leakage of the gas or liquid.

Fitted loosely in the seat 2 of the said rotary-valve 1 is the angular-end 2^a of the combined valve-stem and bottle-holder 4, the outer portion of which is cylindrical, and extends through an aperture formed in the wall of the tank 9, and thence through a stuffing-box 14 having a gland 15 and provided with the usual packing 16.

The outer end of said combined valve-stem and bottle-holder 4 projects free a distance beyond said gland, upon the exterior of said tank, and is fitted with a suitable hand-lever 7, by means of which latter the device may be rocked or rotated, for purposes hereinafter described in detail.

The numeral 5 designates the acid-bottle, preferably of glass, and mounted in a circular-seat 5^a formed in said revoluble combined bottle-holder and foam-valve stem 4, so that when the latter is rotated the con-

tents of the said bottle will be dumped into the liquid contained in said tank 9, for a purpose hereinafter mentioned.

The said bottle 5 may be fitted tightly 5 within its said circular-seat 5^a, so that it will retain its position therein by frictional contact with said seat, or there may be an additional support in the form of a U-shaped wire seat 20, having its arms fixed 10 to the said circular bottle-seat by being passed through apertures therein and riveted or otherwise secured in place, the said wire passing under the bottom of the said bottle, to support the same, as shown in Fig. 5.

15 Said acid-bottle is fitted with a common cover or stopper 6, which rests loosely in place, so that it will fall from the bottle whenever the latter is inverted and drop to the bottom of said tank, where it can be re-covered and used again when the bottle is 20 refilled with acid.

The operation is as follows:

In charging the machine, the tank 9 is filled to a point about half-way up to the 25 top of the bottle 5, with a saturated solution of bicarbonate of soda, with which is mixed a suitable quantity of any common foam-forming substance, or any suitable viscous soluble-in-water substance, such as 30 extract of licorice-root, glue, glucose, soap-tree bark, &c.

Then the acid-bottle 5 is filled with any suitable acid, preferably sulfuric acid.

The acid is thrown into the alkaline solution by turning the handle 7 to a position indicated by dotted lines in Fig. 1, the said bottle being thereby inverted, its cover dropping off and the acid dropping into and commingling with the liquid in said tank, 40 and instantaneously generating a large volume of carbonic-acid gas and creating a heavy pressure in said tank.

Foam, or bubbles, will be formed by the agitation produced by the mixture of the 45 acid with the alkaline solution, and the bubbles will be enlarged or distended by the carbonic-acid gas. With the handle 7 down, the port or discharge-opening 18 of the rotary-valve 1 will be in registration with 50 the foam-discharge opening of the said T 3, and the machine may now be used in extinguishing either oil fires or any other incipient fire.

By opening the cock 13^a of the discharge-55 nozzle 13, the combined foam and liquid will be thrown from said nozzle onto the fire, the bubbles of the foam spreading over the fire and materially assisting in its extinguishment, by reason of the fact that said bubbles are filled with carbonic-acid gas, which is not combustible.

In ordinary fires, where no oil is present, it may not be necessary to discharge any foam or bubbles, and in that case the operator turns the handle 7 back to the position 65

in which it is shown in Figs. 1 and 5, and leaves it there, which will rotate said foam-valve 1 and cut off the exit of foam or liquid by way of the discharge-opening of the discharge pipe T 3, so that the only pathway 70 for the escape of liquid from said tank will be through the said strainer 10 and pipe 11.

The liquid being thus discharged from the bottom of the tank, will be liquid only, as the foam or bubbles are located at or near 75 the surface of the liquid in the tank.

It will thus be seen that I have provided a means, in a single unobstructed tank, for projecting either foam or a liquid, or a combination of foam and liquid, as required. 80

From the above description, taken in connection with the drawing, it will be clear that I have provided a single valve which may be termed a "proportioning" valve, which (when moved in the desired direction 85) controls and limits within a reasonable range the proportion of foam and liquid that is discharged, as required for the service mentioned.

For instance, by moving the valve 1 to a 90 more or less open or closed position, the foam-discharge opening of the said discharge-pipe T 3, will thereby be more or less opened or closed, with the result that more or less foam and liquid will be discharged by the machine.

In oil fires, a free flow of foam should be permitted for an obvious reason.

By reason of the described construction and operation of my invention, I am enabled to use one apparatus for either oil fires or ordinary fires.

At close range, the foam will be found very highly efficient; but as foam cannot be thrown a great distance the liquid should be thrown upon the fire if the same is any greater distance than 15 feet away from the operator.

I do not limit myself to the exact construction shown in the drawings, as the same may be changed by skilled workmen without departing from the scope of my invention.

I claim the following as my invention:

1. The combination, with a single fire-apparatus tank, of an acid-receptacle mounted within said tank to empty an acid into a body of foam-forming alkali contained in said tank; a discharge-pipe for the liquid alkali, extending vertically in said tank from a point near the bottom thereof to a position near the top of same; a discharge-connection, with which the upper end of said discharge-pipe is in communication; a single valve located in said tank near the upper end of said discharge-pipe having a port opening to the interior of the tank and constructed to control the passage of foam from the top of the tank to the said discharge-connection, and arranged when closed to

prevent foam from passing out of said tank, and to allow liquid to pass freely to said discharge-connection; and means extending from said single valve to said acid-receptacle and to the exterior of the tank, to move said acid-receptacle and said single valve simultaneously.

2. In a chemical fire-apparatus, a tank, a discharge connection for said tank, a suitable valve located on the interior of said tank to control the passage of foam to said discharge-connection, a combined acid-bottle holder and valve-stem connected to said valve and extending out through the wall 15 of said tank to the exterior thereof, a handle

on the projecting portion of said combined acid-bottle holder and valve-stem, for rotating the latter from the exterior of said tank, and an acid-container mounted upon said combined acid-bottle holder and valve-stem, 20 and adapted to be discharged of its acid by the rotation of the said combined acid-bottle holder and valve-stem.

In testimony whereof I have signed my name to this specification, in presence of two 25 subscribing witnesses.

OSCAR J. HOLMES.

Witnesses:

HENRY L. HIGDON,
JOHN C. HIGDON.
